(22) Filed: **Jan. 26, 2017**

(57) **CLAIM**

The ornamental design for a pen, as shown and described.

(30) **Foreign Application Priority Data**

DESCRIPTION

Jul. 28, 2016 (CN) 2016 3 0350525

FIG. 1 is a front right perspective view of a pen showing my new design.

(51) **LOC (11) Cl.** **19-06**

FIG. 2 is a front elevational view thereof.

(52) **U.S. Cl.**

FIG. 3 is a right side elevational view thereof, with the left side elevational view being a mirror image of the right side elevational view.

USPC **D19/176**; D19/906; D19/904

FIG. 4 is a rear elevational view thereof.

(58) **Field of Classification Search**

FIG. 5 is a top plan view thereof.

USPC D19/196, 187, 179, 177, 176, 175, 173,

FIG. 6 is a bottom plan view thereof.

..... D19/169, 153, 117, 113, 164, 906, 904

FIG. 7 is an enlarged top plan view thereof.

CPC B43K 24/03; B43K 23/12; B43K 23/001;

FIG. 8 is an enlarged bottom plan view thereof.

..... G09B 5/04; G06F 3/03545

FIG. 9 is a front right perspective view of a second embodiment of a pen showing my new design.

See application file for complete search history.

FIG. 10 is a front elevational view thereof.

(56) **References Cited**

FIG. 11 is a right side elevational view thereof, with the left side elevational view being a mirror image of the right side elevational view.
